(57) **CLAIM**

The ornamental design for a picture frame array, as shown and described.

DESCRIPTION

FIG. 1 is a perspective view of a picture frame array showing my new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a perspective view of a second embodiment of my new design.

The dashed lines in FIGS. 1-7 represent environmental subject matter and form no part of the claimed design. The dotted lines shown in FIGS. 1, 2 and 7 represent the border between claimed subject matter and unclaimed environmental subject matter and form no part of the claimed design.

1 Claim, 5 Drawing Sheets
